ABSTRACT

Apparatus for reproducing sound recordings from a multi-track tape in a cassette or cartridge including a number of detecting heads each mounted for detecting signals from one of the tracks and a electronic switch for coupling each of the heads in turn to a sound producing circuit. Track changing can be initiated by detection of a period of silence exceeding a fixed time interval. The apparatus is preferably started on the same track by the insertion of a cassette or cartridge into the apparatus.

**MAGNETIC TAPE PLAYBACK UNIT WHICH
SEQUENTIALLY SWITCHES BETWEEN FOUR
TRACKS BY DETECTING END OF TRACK
SILENCE**

The invention relates to an apparatus for reproducing of recordings on magnetic tapes containing several tracks and more particularly on magnetic tapes in mini cassettes or on endless-loop cartridge tapes.

Such devices now employed require manual return of the cassette to pass from one track to another, the direction of unravelling of the tape being unchanged. Current devices thus are not appropriate for providing background music in areas such as, for example, large department stores, large open areas, restaurants, cafes, etc. because the repeated and frequent manual intervention required results in personnel interruptions and costs which render the apparatus impractical. The ideal solution is endless sound which does not require intervention and which operates with high reliability.

This solution is provided by the use of an endless single-track magnetic tape, but the problem is that such a tape lacks variety, the same music or message being replayed too frequently. In order to prevent boredom and to diversify the transmission, the tape can be frequently changed. This is a smaller inconvenience than effecting manual return, but still a substantial one.

To remedy this problem it has been proposed to use electromechanical devices generally called "plates," either a two-directional plate for two-track magnetic tape cassettes or a one-directional plate for two-track endless tape cartridges, these plates including a playback head with two heads. In both cases, the changing of tracks is done by changing the head from which the reproduction is derived and in the case of a cassette by also changing the direction of unravelling of the tape. These changes are done either mechanically, the tape arriving at its end, stretching and then shifting a lever activating a switch, or electrically, the tape having a conducting capsule, or else a perforation permitting closing or opening the circuit of a switch. In the two cases, the relays act to change the head and eventually the direction of unravelling. Any track change which begins with the stretching of the tape is unacceptable for continuous operation devices since that tape breaks easily because of the jolt resulting from the abrupt stopping of the tape. Added to this disadvantage is the fragility of the control and the resulting unreliability. The operating costs are then burdened with the cost of frequent breakdowns.

Changing by electrical contact at the end of the tape or at the end of recording, is also to be avoided because of the near-impossibility of replacing one of the recordings by another resulting from the unchanging overlapping of the tape by the contact.

The present invention relates to an apparatus for reproducing recordings on magnetic tape having a number of tracks greater than two and capable of operating in continuous transmission without any manual intervention other than the initial placement of the cassette or the cartridge. This transmitter has entirely electronic control of track selection and reversal of the direction of unravelling.

The invention relates more particularly to a reproducer of the type discussed above containing an attached electronic device termed an "inhibitor" which prevents two successive change-overs during the same

silence, which is the time just before a new modulation is detected. This inhibitor is, however, rendered inoperative by a safety device acting at the end of the magnetic tape if it is unwound without the playback head encountering a recording.

Other particulars and advantages of the invention will appear during the course of the description which follows and which, made with reference to attached drawings given by way of non-limiting examples, will easily show how the present invention can be put to use.

BRIEF DESCRIPTION OF THE DRAWINGS

- FIG. 1 shows the principal component elements of an apparatus in accordance with the invention.
- FIGS. 2 to 5 inclusive represent the mechanical part of this apparatus, characterized by one type of Plate.
- FIGS. 6 and 7 represent a second type of plate having three motors.
- FIG. 8 shows the order of succession of the playbacks of the tracks and the direction of unravelling for each one of them.
- FIGS. 9 and 10 are views of electromechanical means which can act on the switch for changing tracks.
- FIG. 11 is a modular drawing of the electronic part of the transmitter reduced to its essential elements.
- FIG. 12 is a modular drawing of this same electronic part, the pulse generator being the device represented in FIG. 9.
- FIG. 13 is a drawing of the switching device.
- FIG. 14 is a table giving the pressures applied at the inputs of the switch when the playback-output connection is established for one of the tracks.
- FIG. 15 is a drawing showing the audio amplification circuit and the integrated circuit.
- FIG. 16 is a drawing of the "levers" module.
- FIG. 17 is a drawing of the decoding device.
- FIG. 18 is a drawing of the level adjustment device.
- FIG. 19 is a drawing showing a variation of the levers module.
- FIG. 20 is a drawing of the decoding device following this variation.
- FIG. 21 is a drawing of the control module of the levers.
- FIGS. 22 and 23 are, respectively, drawings of the switch control devices producing the change in the direction of unravelling of the tape in the case of the plate described with regard to FIGS. 2 to 5.
- FIG. 24 is an operating diagram of the switch controls.
- FIG. 25 is a drawing of the electronic part when the generating pulse finds its origin in a modulation command to the output of an amplifier of the sound circuit.
- FIG. 26 is a drawing of a circuit discriminating two lengths of time of absence of modulation, permitting the levers to receive the control pulse from an absence of modulation noted at the output of one of the audio amplifiers.
- FIG. 27 is a drawing showing operation of this discriminating device.
- FIG. 28 shows the abrupt change in pressure noticed at the time of the switching to the gate of the TEC.
- FIG. 29 is a drawing of the circuit inhibiting the changing of track.
- FIG. 30 is a graph of operation of the latter circuit.
- FIG. 31 is a drawing of a circuit assigning the first track when the cassette is put into place.

FIG. 32 is a drawing of operation of the latter circuit.

FIG. 33 is a drawing of combined operation of the levers, decoding device, level adjuster and switching device.

FIG. 34 is a drawing of the electronic part not including a sound level module.

FIGS. 35-36, 37-38 and 39 are, respectively, drawings of the modules: control of levers, discriminator and inhibitor, first track selector proper to the sketch in FIG. 34.

FIG. 40 is a drawing of the control of switches of the plate with three motors.

FIG. 41 is a drawing of the connections of these three motors.

DETAILED DESCRIPTION OF THE DRAWINGS

The description which follows relates to a reproducer of sound recordings on a magnetic tape in a mini-cassette and containing a number of even tracks greater than 2 (usually a minimum of 4). As can be seen in the block diagram in FIG. 1, this apparatus includes a mechanical plate of known type (either the one which can be seen in FIGS. 2 to 5 or the one shown in FIGS. 6 and 7) causing the magnetic tape to pass in front of a playback head including as many detecting gaps as there are tracks recorded on the tape. The playback head is connected to a conventional audio output device (amplifiers-loudspeakers, etc.) through a static electronic switch. The various functions of the plate are controlled by the control circuit.

In principal the placement of the cassette into the plate produces the initial impulse for starting it on its course. Under certain conditions, however, which will be discussed below, the absence of modulation detected by the audio device causes stopping of the apparatus.

Prior to going into the description of parts concerning the invention it is appropriate to describe the two types of plates which can be used as the mechanical part of this transmitter.

FIGS. 2 to 5 are level-view sketches of the first type of plate according to various horizontal planes superimposed. As can be seen by examining these figures, this plate includes in a frame (not shown) a motor fed and controlled by the general feed unit which is itself connected to a current source, the motor driving always in the same direction, by its pulley and a belt, the two capstans C_{b1} and C_{b2} which turn in a direction opposite to one another about spindles A_1 and A_2 respectively.

The spindles (axles) A_1 and A_2 as shown in FIG. 2 of these capstans are alternately driven to provide the impetus for moving the magnetic tape shown in FIG. 3 in one direction or the other. The ends of this tape are connected to the reels R_1 and R_2 of a cassette.

As can be seen in FIG. 3, reels R_1 and R_2 are carried respectively by spindles A_3 and A_4 which are in turn mounted on the plate. Spindles A_3 and A_4 are respectively connected for rotation with pulleys P_3 and P_4 (shown in FIG. 3) which are alternately driven by pulleys P_1 and P_2 of FIG. 2. Furthermore, as shown in FIG. 4, the plate supports two rocker members RM_1 and RM_2 pivoting around the fixed spindles A_5 and A_6 . Pressing pulleys PP_1 and PP_2 pivot with respect to these rockers. These rocker members are arranged so that the pressing pulley of one of the rockers tightly applies the tape against the spindle A_1 or A_2 which corresponds

when the rocker in question is in its closest position to the cassette. Rocker members RM_1 and RM_2 also are provided with fingers A_7 and A_8 respectively, which are removed from the pivoting spindles A_5 and A_6 and onto which there are wound torsion springs TS_1 and TS_2 urging each rocker member closer to the position in which its pulley PP_1 or PP_2 is tangent to the spindle A_2 or A_1 . Intermediate pulleys PI_2 and PI_1 , which drive by friction pulleys P_3 and P_4 , pivot about spindles A_{10} and A_9 , sliding in grooves GS_2 (or GS_1 not shown) opposing traction springs TR_2 and TR_1 .

A cam shown in FIG. 5 is alternately shifted in translation by switches A and B guided by fixed spindles A_{11} and A_{12} passing through a slot. This cam has two sets of bosses B_1 and B_2 and B_3 and B_4 situated on both sides. The purpose of these bosses is to shift, respectively, the spindles A_7 - A_8 and A_5 - A_{10} as the cam is itself shifted by switches A and B. In this way the moving of the cam in one of the two directions releases on the one hand one of the rockers by its spindle (for example A_8) in the direction of the cassette so as to halt the friction between pulley PP_2 and spindle A_2 which is driving the tape and on the other hand the spindle of one of the intermediate pulleys (for example A_{10}) to suppress the driving of the corresponding reel (for example R_2) by this pulley from A_2 . Thus, there is synchronization of the movement of the one of the devices which is driving the tape and of the corresponding rethreading reel.

As shown in FIG. 3, the tape passes in front of a playback head which includes as many detecting gaps as there are tracks of recording on the tape. Accordingly, for this arrangement we can alternatively use a two-directional plate with three motors of the type shown in FIGS. 6 and 7. As can be seen in these figures, this plate has a fixed chassis and a moving chassis.

The fixed chassis has on the one hand a main motor driving a belt to turn two capstans Cb_1 and Cb_2 , in opposite direction, the respective spindles of which A_1 and A_2 , serve as a drive pulley for the tape and on the other hand two secondary or auxiliary motors MA_2 and MA_3 each one of which is connected to a reel-carrying spindle A_3 or A_4 . The motors MA_2 and MA_3 are motors with weak coupling which provide for the perfect rolling up of the tape onto the reel in question. Naturally these motors operate alternately, and their speed is reduced by the tape to a speed corresponding to the movement of the tape. Their action on the reel provides a tension of the tape which is favorable for proper winding.

As shown in FIG. 7, the fixed chassis has grooves into which the cassette CS is placed which pushes the Lugs 1 and 2 in opposition to the springs RS_1 and RS_2 and cause the levers LEV_1 and LEV_2 to pivot about a spindle (axis) passing through the cam-cutter CAM , this spindle being connected to the moving chassis.

The moving chassis is connected to the fixed chassis by four parallel links (not shown in the drawing) forming with the structures of the chassis a deformable parallelogram such that the plane of the mobile chassis approaches the plane of the fixed chassis by pivoting according to the lower spindles of these links. Springs tend to spread apart the mobile chassis.

The fixed chassis mounts the playback head which is provided with four detecting gaps, the pressure rollers (pulleys) PR_1 and PR_2 of the rockers R_1 and R_2 vibrating against the springs RS_1 (or RS_2) according to their axis A_{15} . The magnetic tape passes between the spindle-

pulley A_1 and the pressing pulley PR_1 and between the spindle-pulley A_2 and the pressure pulley PR_2 . Since the spindle A_1 is connected to the capstan Cb_1 and the spindle A_2 is connected to the capstan Cb_2 , and these two capstans turn in opposite directions, the tape will be driven in one direction or the other according to the couple of pulleys (A_1/PR_1 or A_2/PR_2) which then work together as the result of the stimulus imparted by one of the switches A or B acting on the rocker member R_1 or R_2 . Further, switch A or switch B is placed under pressure in synchronization with further switch controlling the rotation of the corresponding auxiliary motors MA_2 and MA_3 .

A recess lever is connected on the one hand to the mobile shank in FIN and on the other hand to the mobile shank of a switch (relay) C, a spring RS_7 causing the rotation about FIN . At the position in which the two chassis are close to one another, the recess lever engages the STOP. Recess lever and this STOP constitute the locking mechanism, the relay switch C providing the unlocking.

The two types of plates which have just been described have not been used up to now except for cassettes with two-track magnetic tapes. The use of tapes having four or more tracks makes it impossible to apply a switch-over by a simple reversal and makes it necessary to use more complicated switching devices. The switching is, however, simplified if a certain order is adopted in the direction of movement of the tracks. FIG. 8 shows the direction of movement of a tape having four tracks, T_1 , T_2 , T_3 and T_4 . The first track (T_1) and the second track (T_2) are read from x towards y while the third track (T_3) and the fourth track (T_4) are read from y towards x although the order of reading is $T_1-T_3-T_2-T_4-T_1$, etc.

FIGS. 11 and 12 illustrate two similar embodiments of circuitry for providing signals causing the required transfer from one track to the other, and the change in direction of movement of the tape. The Bistable Rocker circuitry which is described in detail below provides an output on one of its four channels or lines, each corresponding to one of the tracks and indicating from which tracks signals should be derived and applied to the Sound Device. The output of the Bistable Rocker circuitry is applied to a Decoder circuitry which provides appropriate signals on its four output lines connected to the output of the Decoder are the two Command Circuits for the relays RA and RB . In the instance where a plate with three motors is employed appropriate control circuits for the relays are RMA and RMB would also be employed for controlling the rotation of the auxiliary motors MA_2 and MA_3 .

The output of the Decoder circuit is also applied to a level adapter circuit which likewise provides four output lines or channels. The output of the Level Adapter Circuit is in turn applied to a Switch which also receives the electrical signals derived from the respective heads for the four tracks. The Switch couples the correct track to the input to the Preamplifier in the Sound Device. The output of the preamplifier is in turn applied to a Power and an Audio Amplifier for driving appropriate loud speakers and the like.

The shifting of the Bistable Rocker between its four output states is controlled by a Pulse Generator and the Command Circuit which is shown in detail in FIG. 21. The Pulse Generator provides pulses to the command circuit so long as the tape is moving and the command

circuit provides an appropriate signal to the Bistable Rocker causing it to change its output condition when the tape stops, indicating that it has reached its end. In order to cause the equipment to start on the same tape and move in the same direction initially, the closing of Switch K by the insertion of a cassette into the equipment operates a Start circuit to impose a signal on the output of the Bistable Rocker which causes track 1 to be played and the tape to move in the direction associated with that track.

All of the circuits or modules shown in FIG. 11 and 12 are of course powered by the feed unit (FIG. 2) which includes in particular the general switch, the rectifier and the transformer or transformers lowering the voltage of the area to that or those which has or have been selected for the transmitter. In the case which is going to be described, we took a positive voltage equal to $+15$ V, this voltage being the maximum voltage for utilization of the circuit of the sound amplifier and a negative voltage equal to -15 V greater in absolute value than the voltage for which the semi-conductors of the switching device are blocked.

This switch in FIG. 13 has as many basic component switches as there are tracks on the tape. In the case shown in FIG. 13 this switch is composed of four transistors of the field-effect type T_{17} , T_{18} , T_{19} and T_{20} , each one of which is associated with a diode D_{11} , D_{12} , D_{13} and D_{14} . As is well known a field effect transistor FET is a semi-conductor device presenting in its non-conductive state a very high drain-source resistance, and in its conductive state a very low resistance close to 100 ohms so that its characteristic approaches that of a perfect on-off device. In FIG. 13 and in each FET, the drain, the source and the gate are indicated by the letters d , s and g , respectively. The "gate" (input) impedance being an almost infinite 10^6 ohms (several hundreds of Mohms), the input current zero, the voltage gate drain is zero and gate-source voltage not equal to zero, since a FET has no offset voltage. Consequently, T_{17} is conductive, $R_{DS} \neq 0$ and the signal coming from the corresponding track is transferred to the output.

Summarize, the table in FIG. 14 indicates the track from which the signals are transferred to the output as a function of the voltages existing on the inputs Ca_1 , Ca_2 , Ca_3 and Ca_4 from the level adapter. The semiconductor of one of these basic switches is rendered conductive by these voltages for switching one of the gaps to the input of the audio stage, the semiconductors of the other basic switches being non-conductive. The audio circuit includes an audio preamplifier and an audio amplifier of preferably 3 watts, provided with an output capable of handling a conventional external amplifier of high power.

In order to allow the current to pass into one of the FETs of the switch and to block the others, bistable multivibrators or rockers are employed. The Rocker module shown in FIG. 16 has as many bistable rockers or multivibrators as there are component switches, i.e., pairs of magnetic tracks on the tape.

In the circuit which is illustrated in FIG. 16, there are therefore two rockers (T_4-T_5) and (T_6-T_7) in series, the first receiving the command signal appearing at S_1 through the transistor T_8 . Each rocker serves as an input to two of the channels, respectively (Ca_1 , Ca_2) and (Ca_3 , Ca_4). In a conventional manner T_4-T_5 and T_6-T_7 form a bridge.

A bistable rocker has two stable states which complement each other and that in order to change the state it is necessary to provide it with an impulse. If we assume that the transistor T_4 is saturated, its collector is at the potential 0 V, the base of T_5 is at 0 V and T_5 is blocked. Its collector is at +15 V and the voltage base emitter of T_4 is greater than 0.7 V so that T_4 is saturated. The rocker is well into a stable state. It is the signal of command +15 V arriving at S_1 which changes this state. This signal is differentiated by the circuit C_3R_2 and for a short moment of time we obtain a positive voltage on the base of the input transistor T_8 which becomes saturated. During this moment, the collector of T_8 is brought to 0 V. Diode D_1 is blocked, since T_4 is saturated, and no change in potential is transmitted by this diode. Diode D_2 , however, becomes conductive and reduces the potential of the collector of T_5 to 0 V so that T_4 is blocked and T_5 becomes saturated. The rocker remains in this position after the disappearance of the command impulse since it is the second stable state.

The second rocker is triggered by the saturation of T_5 . The negative signal is differentiated and acts in the same manner as the saturation of T_8 . The signals leaving the rocker module are decoded in a decoding module placed between the rocker module and the switch as shown in FIGS. 11 and 12.

The four channels Ca_1, Ca_2, Ca_3 and Ca_4 coming out of the outputs BB_1, BB_2, BB_3, BB_4 of the rocker module enter into the decoding device shown in detail in FIG. 17 and leave it by the outputs DD_1, DD_2, DD_3 and DD_4 . This decoding device on the line +15 V contains, distributed on each of the channels, the four pairs of diodes $D_3, D_4, D_5, D_6, D_7, D_8$ and D_9, D_{10} of identical operation.

For example, for the pair D_3D_4 the signals are to be considering arriving at BB_1 and BB_3 which vary from the value 0V to +15 V, and consequently, the following four cases can occur:

	1st case	2nd case	3rd case	4th case
BB_1	0 V	0 V	+ 15 V	+ 15 V
BB_3	0 V	+ 15 V	0 V	+ 15 V

45

If we compare this table to the one in FIG. 14, we see that it is necessary to change the level 0V. To do this, the level adjuster device shown in detail in FIG. 18 is connected to the lines +15 V, -15 V, so that the level adjuster follows the decoding device. This device transposes a level varying from 0 to 15 V existing at its inputs DD_1, DD_2, DD_3, DD_4 into levels varying from -15 V to +15 V without inversion of the Boolean significance in $DD_1/AN_1, DD_2/AN_2, DD_3/AN_3$ and DD_4/AN_4 . Each input, such as DD_1 , is connected to its corresponding output, such as AN_1 by the set of two transistors, such as T_9, T_{10} and the operation occurs as follows. If the potential $VDD_1 = + 15$ V, the base of T_9 is at +15 V, the voltage base-emitter is zero and the transistor T_9 is blocked. The collector is at -15 V, therefore the base of T_{10} is at -15 V. The base-emitter voltage of this transistor is therefore zero and the transistor T_{10} is blocked. Consequently the potential $VAN_1 = + 15$ V. If $VDD_1 = 0$ V, the base-emitter voltage of the transistor T_9 is greater than 0.7 V, this transistor is saturated and its collector is at +15 V. The base-emitter voltage of T_{10}

is greater than 0.7 V. Thus, this transistor is saturated and the potential $VAN_1 = - 15$ V.

The functioning is identical for DD_2/AN_2 with the transistors T_{11}, T_{12} , for DD_3/AN_3 with the transistors T_{13}, T_{14} and for DD_4/AN_4 with the transistors T_{15}, T_{16} . The signals coming from AN_1, AN_2, AN_3, AN_4 enter into the switching device which couples one of the tracks to the output which constitutes the input of the audio preamplifier. The level adjuster is necessary in this embodiment because the module of rocker is fed with +15 V/0 V.

FIG. 19 illustrates a module comprising a variation of the rocker module, but supplied in +15 V/-15 V. The makeup of the module of FIG. 19 is similar to that in FIG. 16. If we assume that the transistor T_4 is saturated, its collector is at the potential +15 V. The base-emitter voltage of T_4 is greater than 0.7 V, so that T_4 is saturated. The rocker is well into a stable state. It is the command signal +15 V arriving at S_1 which changes this state. This signal is differentiated by the circuit C_3R_2 .

When T_8 is saturated its collector is brought to -15 V, the diode D_1 is blocked because T_4 is saturated and no change in potential is transmitted by this diode. Diode D_2 , however, becomes conductive and brings the potential of the collector of T_5 to -15 V so that T_4 is blocked and T_5 is saturated. The whole remains in this position after the disappearance of the command impulse, since this is the second stable state. The second rocker is released by the saturation of T_5 . The negative signal is differentiated and acts in the same manner as the saturation of T_8 . The four channels Ca_1, Ca_2, Ca_3 and Ca_4 coming from the rocker module of FIG. 19 by the outputs BB_1, BB_2, BB_3, BB_4 enter the decoding device shown in FIG. 20 and leave it respectively at DD_1, DD_2, DD_3 , and DD_4 . The decoding device of FIG. 20 on the line +15 V has, distributed on each one of the channels, the four pairs of diodes $D_3, D_4, D_5, D_6, D_7, D_8$ and D_9, D_{10} whose functioning is identical. For example for the pair D_3D_4 consider the signals arriving at BB_1 and BB_3 which vary from -15 V to +15 V. Consequently the following four cases can occur:

	1st case	2nd case	3rd case	4th case
BB_1	-15 V	-15 V	+ 15 V	+ 15 V
BB_3	-15 V	+ 15 V	-15 V	+ 15 V

In contrast to the case of the preceding modules, in this new case there is no need for the level adjuster since a negative front on S_1 or S_2 positions T_4 and T_5 . As we see, the problem of the switching poses the problem of the change of stable state of the rockers by an impulse received by them.

This impulse can be originated by the abrupt closing of a circuit, this closing obtained by conventional methods such as the presence of a conducting path on the tape or of a perforation making it possible to create an electrical contact. Any device can also be used which is sensitive to the mechanical pressure of the tape at the time when it reaches the end of its path.

Nevertheless, it is desirable to avoid any marking whatsoever on the magnetic tape in such a way as to remain free from the length of the replacement recordings after erasure, as well as to avoid the intervention of moving mechanical elements since the functioning

of this kind of elements is not safe enough to assure permanent service without risk.

Since as a rule the initial impulse is transmitted to the rockers by means of a command module as shown in FIG. 11 and FIG. 12, it is advantageous to use a pulse generator of the type shown in FIGS. 9 and 10.

The pulse generator shown in FIG. 9 has a drum which is connected to the spindle A_4 for winding the reel. This drum has an endless conducting track of variable length and equipped for example with recesses or notches. Against this drum there rub the three diagrammatically illustrated branches PL_1 , PL_2 , PL_3 of a feeler. These branches being arranged so that the central branch PL_2 is always in contact with the median axis of the track whereas the side branches rub either on the areas CR_1 or CR_2 of the drum, external to the track, or on the outgrowths of it. FIG. 12 is a sketch in which the pulse generator is the one which has just been described referring to FIG. 10.

FIG. 21 is a detailed diagram of the command circuit of FIG. 12 which provides one output when the tape is moving and a second when it is stopped. This circuit, interposed with capacitances and resistances between the conducting feelers PL_1 , PL_2 , and PL_3 of the pulse generator and the polarities $+15$ V and 0 V, is constructed essentially of a transistor T_1 combined with a Schmitt trigger T_2-T_3 with output S_1 towards the rockers. When the two feelers PL_1 and PL_2 are connected, the capacitor C_1 is charged to 15 V through the resistance R_1 and remains charged when the feeler PL_2 is alone on the metalized track. When PL_2 and PL_3 are connected, C_1 discharges in the base circuit of the transistor T which becomes saturated, whereas its collector is at 0 V. Then, when PL_2 is alone again, T_1 is blocked, but by the capacitor C_2 located between its collector and its base, the voltage at the collector rises very slowly. Then PL_1 and PL_2 are connected again and the above steps repeated. During this time, the Schmitt Trigger T_2-T_3 during each cycle converts the slow change in potential of the collector of T_1 into an abrupt change from 0 V to $+15$ V. The interval between two saturations does not present any problem since the capacitor C in the Schmitt Trigger has a value such that the time constant is very long in front of that interval. When the magnetic tape is blocked its tracks are fixed and stopped. If PL_2 is alone connected then T_1 is blocked. If PL_1 and PL_2 are connected then T_1 is blocked and the capacitor C_1 remains charged at $+15$ V. If PL_2 and PL_3 are connected then C_1 discharges into T_1 which is blocked when this capacitor is discharged.

Therefore regardless of the relative positions of the feelers PL_1 , PL_2 and PL_3 , T_1 is non-conductive. The potential at the collector rises slowly towards $+15$ V and when the threshold of the trigger is attained, then the output S_1 passes abruptly from 0 to $+15$ V and acts on the rockers. When the driving spindle A_4 of the tape turns again, then T_1 is saturated and S_1 returns quickly from $+15$ V to 0 V. It has been stated previously that these changes in voltage constitute the modifying signal of the steady state of the rockers and therefore cause the track change.

In the case of a cassette with many tracks, since it is necessary to reverse the direction of movement at the same time that the track is changed, the command devices A (FIG. 22) and B (FIG. 23) of the relays RA and RB causing the translation of the cam are connected to the output of the decoding device. The command de-

vice A of FIG. 22 is connected to output DD_2 and DD_4 of the decoder. Two transistors T_{21} and T_{22} form a logical OR, i.e. the command by DD_2 or DD_4 activates the relay RA which functions under -24 V. A third transistor T_{23} reverses the signal available on the collectors of T_{21} and T_{22} whereas two other transistors T_{24} and T_{25} form a Darlington stage of high gain in current and feedback.

In what follows we will only describe the command by DD_2 . To pass from track T_1 to track T_3 , DD_2 passes from 0 to $+15$ V. This passage is differentiated by the circuit C_4-R_3 and therefore causes a positive pulse on the base of T_{21} which thus saturates during the duration of this pulse.

The transistor T_{23} is also saturated during this pulse and saturates the Darlington pair $T_{24}-T_{25}$. The relay RA therefore has 24 V at its extremities and is activated during this pulse which lasts 100 msec, the time necessary for the response of the mechanics activated by the relay RA. The command device B of FIG. 23 is connected to DD_1 and DD_3 and only differs from the preceding one by the relay RB operating under a voltage of $+15$ V and a pulse duration of 10 msec. The connection is not "Darlington" but "Compound." The operation of the two relays RA and RB resulting from the voltage pulses occurring at DD_1 , DD_2 , DD_3 and DD_4 is summarized diagrammatically in the diagram of FIG. 24.

If we wish to eliminate any constraint, it seems necessary to seek out the origin of the pulse in the absence of modulation at the output of the preamplifier. The diagram of FIG. 25 illustrates this principle. The rockers are connected then to this output through a discriminator which operates as a comparator of the time of silence.

FIG. 26 shows the diagram of the circuits of this discriminator which has the purpose of discriminating the short periods of silence between the signals recorded on a track from long period of silence at the end of a recording and to use this long silence to trigger the pulse for changing tracks.

This discriminator is composed of several stages: E_1 is an impedance adaptor with the gain in voltage $G=1$; E_2 is an amplifier saturated in the absence of signal. When the signal is present at S_3 (signal preamp signals) the negative part of this signal blocks B_2 and S_4 is then at $+15$ V.

The third stage E_3 is blocked when S_4 is at 0 V and is saturated for S_4 at $+15$ V. At the time of a blocking of B_3 , capacitor C_5 discharges into the base circuit of a trigger $T_{26}-T_{27}$ with a time constant which is variable by the adjustable resistance R_4 . When the signal at the base of T_{26} is equal to the threshold of the trigger, then T_{27} saturates and its collector voltage goes abruptly from 0 to $+15$ V. This rising front is differentiated and saturates a transistor T_{28} mounted in parallel to the input transistor T_8 of the module of the rockers. The last two transistors therefore form a logical OR. The saturation of T_{28} therefore causes the track to change.

The threshold of the trigger is such that a silence of time T_1 adjustable from 5 to 8 seconds produces the changing of tracks. A smaller silence time has no effect. It should be noted that the command module of the rockers described previously becomes a module of safety for switching for the case when, for example, one of the tracks is blank. The diagram in FIG. 27 shows graphically what has been described above.

The main difficulty of the switch-over by means of field effect transistors (FET) resides in the sudden change in voltage on the gate of this type of transistor at the time of the switch-over (see diagram in FIG. 28). The gate-source capacity of a FET differentiates this variation and we thus obtain a pulse which is amplified and acts as a signal to substrate the stage E_3 of the discriminator module. Since there is always a period of silence between the switching and the arrival of the next signal on the track we once again reach the threshold of the trigger and we switch over again. FIG. 28 is the diagram of this defect. It is therefore necessary to prevent two successive switchovers during the same silence. This is obtained by requiring the passage of a new modulation to permit the second switching.

FIG. 29 illustrates the inhibition device of the rockers. This device is essentially composed of a Schmitt Trigger T_{31} - T_{32} interposed between two pairs of transistors in series T_{29} - T_{30} and T_{33} - T_{34} .

When S_4 is at 0 V then the transistors T_{29} and T_{30} are blocked, and the capacitor C_6 is discharged. The point B of the Schmitt Trigger is at 0 V, the transistor T_{33} is blocked and T_{34} is saturated and places the base of the transistor T_{28} of the discriminator at 0 V, which blocks it. The switch-over cannot occur. When S_4 is at +15 V, then the transistors T_{29} and T_{30} are saturated, and the capacitor C_6 charges with a time constant T_{33} fixed at 3 seconds. The trigger switches and T_{34} is blocked so that switching can occur. When S_4 passes again to 0 V, then the capacitor C_6 discharges into the Trigger so that T_{34} saturates after a time

$$\Delta T_2 = \frac{3}{2} \Delta T_1$$

and which is varied by means of the adjustable resistance R_s . At the end of the time ΔT_1 , when S_4 is at 0 V the switch-over occurs. However, owing to the fact that $\Delta T_3 = 3s$ and because of the small duration of the parasite, the capacitor C_6 does not have the time to recharge itself. At the end of the time $\frac{1}{2} \Delta T_1$, T_{34} saturates and prevents the new switching. A signal time of ΔT_3 is therefore necessary to once again permit the switching. The operation which has just been described above is illustrated by the diagram in FIG. 30.

Finally it is necessary that the introduction of the cassette into the plate causing selection of the same one of the tracks for example track no. 1, with the same direction of movement. For this purpose, the transmitter has an additional start module. FIG. 31 illustrates this module which has the task of forcing the initial direction of movement by imposing a signal on the outputs of the rocker circuits. It contains essentially a Trigger T_{35} - T_{36} and a transistor T_{37} and two diodes D_{15} , D_{16} on the side of the rockers. The operation occurs as follows.

When the cassette is introduced, a contact K closes and charges capacitor C_7 which discharges almost instantaneously into the Schmitt Trigger and into the two resistances R_6 , R_7 . The resulting positive pulse is shaped by the Schmitt Trigger and its positive side is differentiated by the circuit with time constant C_8 , R_8 . This positive pulse saturates the transistor T_{37} and the two diodes D_{15} , D_{16} , imposing 0 V at the outputs BB_2 and BB_4 . Consequently the outputs BB_1 and BB_3 are at +15 V and the passage onto track 1 is imposed. The diagram in FIG. 32 illustrates this procedure of operation resulting from the insertion of the cassette. The operation of

the rocker, decoder, level adaptor and switch modules is according to the overall diagram in FIG. 33.

FIG. 34 is a modular diagram of the electronic part of a transmitter which does not require level adjustment. As we can see by comparing FIG. 21 and FIG. 35, the two devices for commanding the rockers only differ in the position of the transistor T_8 the collector of which (FIG. 35) is connected to the line +15 V and the emitter to the line -15 V. The output S_1 fluctuates therefore between -15 V and +15 V and vice versa.

If we then compare FIG. 16 and FIG. 19, we notice that the two devices of rockers only differ by the fact that the voltages are +15 V and 0 V for the one rocker and +15 V and -15 V for the other.

As stated previously, the use of a plate with three motors (FIG. 6 and 7) requires a few changes in the circuit, according to the diagram in FIG. 34, as regards the supplying of the relays RA and RB and above all that of the relays RMA and RMB. This modification is shown in FIGS. 40 and 41. FIG. 39 is a complete diagram of a transmitter-reproducer according to the invention and including this plate. The dual feed voltage supply unit receives, from a general switch, the alternating current of the main transformer and includes a general transformer supplying low A.C. voltage to the motors MA_1 , MA_2 and MA_3 and two rectifier units providing the D.C. voltages +15 and -15 V. From the time of the engaging of this general switch, the motor MA_1 starts out and this causes the capstans Cb_1 , Cb_2 to turn. The insertion of the cassette into the grooves moves the pusher from the switch K.

As we can see in FIGS. 39 and 40, not only does this switch K act on the start circuit, but it also controls the command circuits of two pairs of relays RA-RMA and RB-RMB connected respectively, to the channels Ca_1 - Ca_2 (tracks T_1 - T_2) and Ca_3 - Ca_4 (tracks T_3 - T_4). Because of the relationships between BB_1 , BB_2 , BB_3 and BB_4 , only one of these 4 inputs is at +15 V. Therefore, it suffices to analyze the part BB_3 - BB_4 in order to understand BB_1 - BB_2 .

BB_3 OR BB_4 = +15 V therefore
 T_{39} OR T_{38} are then saturated
 T_{40} saturated therefore T_{41} saturated therefore
 PMA feeds and applies the voltage to the motor MA_2 .
 T_{40} is saturated and hence T_{41} is saturated. At the moment of the saturation of T_{41} , C_{10} is not charged and is therefore equivalent to a short circuit. Hence R_{10} does not act and RA, fed at 15 V, is called up and activates the corresponding rocker.

At the end of a time equal to $\Delta T = R_{10} C_{10}$, the capacitor C_{10} is charged and is equivalent to an open circuit. Hence, R_{10} is connected and limits the current in the relays RA to a current equal to its maintenance current. When the cassette is not inserted then the switch K is open, the device for controlling the relays is not supplied, none of the motors MA_2 , MA_3 turns and no pulley presses the tape between a capstan spindle. This situation is also the same when the supply is cut off without removing the cassette.

In the embodiment represented in FIG. 39 comprising a plate with 3 motors, there is no mechanical element having any action whatsoever after the insertion of the cassette into the grooves with as a result the bringing together of the chassis and of the engaging of the switch K by the finger. Thus properly speaking there is no command module B since the pulse is given

to the rockers by this engaging. The command module B and the drum therefore play the safety role.

The invention is applicable to the reproduction of any multi-track magnetic tapes in cassette or cartridge. This reproduction can be either audio or video. Many changes and modifications of the above described embodiments can, of course, be carried out without departing from the scope of the invention. Accordingly, that scope is intended to be limited only by the scope of the appended claims.

What is claimed is:

1. Apparatus for reproducing recordings from a tape having at least four tracks and mounted for movement in a case comprising:

a plurality of magnetic heads each mounted for detecting signals from one of said tracks,
means for moving said tape past said heads,
means for receiving a signal from one of said heads and producing an audio output,
electronic switch means for coupling any one of said heads to said receiving and producing means and means for controlling said switch means to cause each of said heads to be sequentially coupled one at a time to said receiving and producing means to play each of said four tracks and reverse the direction of tape movement after each track has been played including means connected to said receiving and producing means for producing a trigger signal when silence continues for greater than a predetermined length of time, means connected to said trigger signal producing means for reversing the direction of tape movement whenever said trigger signal is produced, means connected to said trigger signal producing means and responsive to said trigger signal for preventing a further trigger signal for a predetermined time after a trigger signal is produced, at least two multivibrators providing four output states each associated with one of said tracks and responsive to said trigger signal to change its output state, the output state determining which of said heads is coupled to said receiving and producing means.

2. Apparatus as in claim 1 wherein said electronic switch means includes a plurality of field effect transistors equal in number to the number of tracks.

3. Apparatus as in claim 1 further including further switch means operable by the insertion of said case into the apparatus and means connected to further said switch means and said controlling means for causing said electronic switch means to couple a predetermined one of said heads to said receiving and producing

means.

4. Apparatus as in claim 3 wherein said switch means couples said head to said receiving and producing means in a predetermined, fixed order.

5. Apparatus as in claim 1 wherein said moving means includes a plate with a single motor driving continuously two capstans turning in opposite directions, two pressure pulleys each of which is carried by a rocker member and tightening alternately the magnetic tape against one of the pulleys of the capstan for the purpose of driving it into one direction or the other, a cam member for alternately shifting the two rockers, said cam being moved alternately by two relays of reverse action, each one of these relays being connected to the corresponding channels of said electronic switch means.

6. Apparatus as in claim 5 wherein each one of the relays is controlled by a device composed of two semiconductors forming a logical OR circuit and a Darlington amplifying stage with large gain feeding the associated relay.

7. Apparatus as in claim 1 wherein said moving means includes a plate with three motors comprising on the one hand, on a mobile chassis, a main motor producing the driving of said magnetic tape by means of two capstans of reverse rotation, two auxiliary motors with weak coupling placed alternately in service and controlling the rotation of the winding reel, and, on the other hand a fixed chassis carrying the cassette comprising two relays each one of which moves a pressure pulley of the magnetic tape against the spindle of the adjacent capstan, means for locking and unlocking said mobile chassis with respect to the fixed chassis of the plate, means for keeping the mobile chassis in the low position, means acting against these maintenance means when the cassette is inserted into the fixed chassis and means for bringing this mobile chassis to the high position during the unlocking, relays and motors being controlled from a general supply unit supplying the necessary currents, and two further circuits for controlling in synchronization a pair of relays, one of the relays for activating the pressure pulley and the relay of the auxiliary motor corresponding to it.

8. Apparatus as in claim 7 wherein each module of control of said pair of relays comprises a circuit in logical OR receiving said signals from two decoding channels, the signals coming out of the logical OR circuit being amplified to make it possible to activate the relays concerned.
